UNITED STATES PATENT OFFICE.

LEE P. HYNES, OF CHICAGO, ILLINOIS.

VENTILATOR.

1,077,078.

Specification of Letters Patent.

Patented Oct. 28, 1913.

Application filed January 2, 1913. Serial No. 739,674.

To all whom it may concern:

Be it known that I, LEE P. HYNES, a citizen of the United States, residing at Chicago, Cook county, Illinois, have invented certain new and useful Improvements in Ventilators, of which the following is a specification.

My invention relates more particularly to ventilators for cars, and in the accompanying drawing and following description is more specifically disclosed in connection therewith; it will be obvious, however, that with or without minor modifications it may be adapted to other similar uses such as in the ventilation of the rooms of stationary structures, etc., one such modification being also illustrated and described hereinafter.

It is well recognized as a requirement of a successful ventilator, that it should have the capacity for exhausting large volumes of air from the compartment to which it is applied without, however, causing the exhausted air to move at great speed, thus constituting a draft, a large cross-section being essential for the purpose. It is further desirable that while the ventilator shall present large openings to the outer air to accommodate the passage of great volumes of air, it shall not expose the compartment to drafts or permit rain to beat into the same. By my invention it is possible to construct ventilators having these desired characteristics in a marked degree, and in which the necessary suction is obtained for exhausting the air without movable parts and under substantially all conditions of service.

In the accompanying drawings forming part of the application and in the detailed description I have set forth a preferred form or embodiment of my invention and also a modification thereof; but it is to be understood that the specific disclosure is for the purpose of exemplification only, my invention not being limited thereto, and I have endeavored to point out the novel features and scope of the invention in the following claims without, however, relinquishing or dedicating any part thereof to the public.

Referring to the drawing, Figure 1 is a perspective of so much of the exterior of a car as is necessary for an understanding of my improved ventilator, showing the latter attached thereto; Fig. 2 is a vertical transverse section upon the line 2-2 of Fig. 3,

and Fig. 3 is a central longitudinally vertical section upon the line 3-3 of Fig. 2, and Fig. 4 a modification especially adapted to an opening in a horizontal roof.

In Fig. 1 the reference letter A indicates the low vertical wall between the lower deck B and the upper deck C of a car. My improved ventilator is shown at D applied to an opening in a pillar between adjacent deck sash E-E in the vertical wall, though, as above indicated, it might be secured to the sash or otherwise located with reference to the car body, or even be used in connection with other compartments to be ventilated whether movable or stationary. As shown, it consists in a sheet metal construction embodying a generally horizontal flue or air passage F, terminating at one end in a flange G to be screwed or otherwise secured about a ventilating opening in the car, and at the other end in a vertical wall H which closes the outer end of the flue except for upwardly and downwardly directed branch flues J-K which extend the entire width of the flue, as best seen in Figs. 1 and 2, and are of considerable cross section as shown in Fig. 3. The upper branch is shown as extended downwardly at J¹ some distance into the flue, though this is not essential, but the lower branch terminates flush with the floor L of the flue which slopes downwardly thereto for a purpose which will appear. Both of the flues are subdivided throughout by numerous partitions N which may be rectangularly arranged, as shown, forming a considerable number of smaller flues or passages. It will now be apparent that the outer ends of the branch flues are exposed more especially to horizontal currents of air which may be due either to the motion of the car or other structure to which they are attached or to the prevailing winds. In either event the air currents passing over and under the upper and lower branches respectively have an ejector action, as will be readily understood, drawing the air from the interior of the compartment. By reason of the numerous partition walls, each of which contributes individually to the action, the suction offset is very greatly increased and any tendency to form swirls or eddies in the air which would interfere with the suction is avoided. In the case of vertical or inclined currents of air the device also acts with great efficiency, any inclination or lateral motion of the currents being

substantially eliminated by the relatively long and narrow passages or flues, by reason of which the air entering from above or below is directed across to the opposite branch.

5 flue and escapes therefrom, at the same time exerting an ejector action on the air within the compartment and main flue. Furthermore, there being no direct passage into the compartment, there can be no back draft 10 due to air movements outside the car. This construction also avoids rain being driven into the compartment since in order to pass through the subdivisions of the upper flue it must fall in a very nearly vertical direction 15 and pass out the lower flue, and any rain which does not pass directly through, is received upon the sloping floor L of the flue and flows out through branch flue K.

The modification shown in Fig. 4 embodies 20 the same principle of operation described in connection with the preceding form of the device. It comprises a central vertical flue P having a flange Q at its lower end for attachment to a substantially horizontal roof formed with a ventilating opening with which said flue connects. At its upper end the flue P communicates with an annular flue F' which in turn opens into upwardly and downwardly extending 25 branch flues J²—K' similar in function and operation to the flues J—K of the first described modification. A concentric disk R immediately covers the flue P to prevent direct entrance thereto or egress therefrom 30 and said disk is provided with a depending flange R' which forms the inner wall of the annular flue J². Flues J²—K' are subdivided in substantially the same manner as are the flues J—K of the modification 35 previously described and for a similar purpose. The operation of this form of the device will be apparent from what has already been said, it being understood that the central flue P has the function of conveying 40 the air to the annular flue F' from which it is drawn by the action of the flues J² and K'.

It will be understood, of course, that the form of the device may be widely varied, the 45 two modifications described being, however, the preferred forms thereof.

I claim:

1. A ventilator comprising a main flue F and a branch flue extending transversely 50 thereto having a series of longitudinal partitions therein.

2. A ventilator comprising a main flue F having means for securing it in horizontal 55 position and a vertical branch flue having a series of longitudinal partitions therein.

60 3. A ventilator comprising a horizontal

main flue and a vertical branch flue partially extending into the main flue and provided with a series of longitudinally extending partitions.

65 4. In a ventilator, a horizontal main flue adapted to connect at one end with the compartment to be ventilated and provided at the other end with a substantially vertical wall and a branch flue connected to the main flue and provided with a series of longitudinally extending partitions.

70 5. A ventilator comprising a horizontal main flue open at one end and adapted to be connected to the compartment to be ventilated, and upwardly and downwardly extending transverse flues at the other end of the main flue, the upwardly extending branch being provided with a series of longitudinal partitions.

75 6. A ventilator comprising a horizontal main flue adapted to connect at one end with a compartment to be ventilated, and upwardly and downwardly extending transverse flues at the other end thereof, each provided with a series of longitudinally extending partitions.

80 7. A ventilator comprising a horizontal main flue adapted to be connected at one end with a compartment to be ventilated and closed at the other end, and upwardly and downwardly extending transverse flues at the other end thereof, each provided with a series of longitudinally extending partitions.

85 90 8. A ventilator for cars and the like comprising a horizontal flue open at one end for connection to the compartment to be ventilated and closed at its outer end, an upwardly extending branch flue communicating with the main flue, a downwardly extending branch flue also communicating with the main flue, the floor of the main flue being inclined upwardly from said downwardly extending branch flue.

95 100 105 9. A ventilator comprising a substantially horizontal flue F open at one end and adapted to be connected to the compartment to be ventilated and closed at the other end by a wall H, an upwardly extending flue J adjacent the end wall and provided with a series of longitudinally extending partitions, a downwardly extending branch flue K likewise provided with a series of longitudinally extending partitions, the floor L 110 of the main flue being inclined substantially as shown and described.

LEE P. HYNES.
